CLAIM

I claim the ornamental design for a cage-shaped pet toy design, as shown and described.

DESCRIPTION

FIG. 1 is a perspective view of the cage-shaped pet toy design; FIG. 2 is a front view of the cage-shaped pet toy design; FIG. 3 is a rear view of the cage-shaped pet toy design; FIG. 4 is a right side view of the cage-shaped pet toy design; FIG. 5 is a left side view of the cage-shaped pet toy design; FIG. 6 is a top/bottom mirror image of the cage-shaped pet toy design; and,

FIG. 7 is a perspective view with a tennis ball in phantom, of the cage-shaped pet toy design.

The broken lines illustrating the ball inside FIG. 7 are for illustration only and form no part of the claimed design. This design invention relates to a cage-shaped cube for use as a pet toy wherein a ball may be inserted.
